UNITED STATES PATENT OFFICE.

WILLARD H. GILMAN, OF NEW YORK, N. Y., ASSIGNOR, BY MESNE ASSIGNMENTS,
TO JOHN A. McVICKAR, OF NEW YORK, N. Y.

RECORDING AND REPRODUCING MECHANISM FOR PHONOGRAHS.

1,389,430.

Specification of Letters Patent. Patented Aug. 30, 1921.

Application filed October 13, 1919, Serial No. 330,464. Renewed July 19, 1921. Serial No. 485,847.

To all whom it may concern:

Be it known that I, WILLARD H. GILMAN, a citizen of the United States, and resident of New York, in the county of New York and State of New York, have invented certain new and useful Improvements in Recording and Reproducing Mechanisms for Phonographs, of which the following is a specification.

- 10 This invention relates to phonographs and more particularly to a mechanism which may be used as an attachment to phonographs of standard make, or incorporated in the mechanism of the phonograph itself, for 15 making and reproducing records of the disk type. Among other things its objects are to provide a mechanism which will accurately drive the stylus or operating jewel connected with the diaphragm across the 20 face of the record so as to follow a closely formed spiral on the face of the record; a means whereby the stylus may be accurately positioned anywhere on said spiral; a convenient means whereby the stylus may be 25 elevated from the record; a means whereby the elevation of the stylus suspends its driving operation; a means whereby the stylus is automatically elevated and its driving 30 operation suspended when it reaches a pre-determined point on the face of the record; a means whereby the stylus receives its driving motion from the turntable of the phonograph; a means for compensating for eccentricity and irregularities of this drive, 35 a means for adjusting the mechanism for various sizes of turntable and height of record; a means for rapidly removing the mechanism from and replacing it on the turntable of the phonograph and a means 40 for producing a continuous voice passage from a fixed speaking tube to the moving diaphragm.

Other objects will appear from the following specification and drawings in which, 45 Figure 1 is a side elevation of the mechanism partly in section applied to a phonograph, Fig. 2 is a plan view corresponding to Fig. 1 with part of the cover sectioned to show the interior construction, 50 Figs. 3, 4 and 5 are detail structural features of my invention partly sectioned to show the method of operation. Detail A is a side elevation of the releasing mechanism.

This mechanism includes a friction clutch 5 with a universal joint attached to the center

stem of the turntable and by means of a worm gear and horizontal shaft, the rotation of the turntable is transmitted by a reduction gear to a vertical shaft near the edge of the record. This shaft carries the 60 tone arm and as it rotates it moves the tone arm from the edge toward the center of the record causing the stylus to make a close spiral on the surface of the record as it rotates. By a cam action this vertical shaft 65 may be elevated and through a friction clutch released from the driving mechanism. This movement also raises the tone arm from the record. The mechanism turns on a pivot and may be turned over the body to 70 clear the turntable for replacing records.

In the drawings 11 indicates the top of a disk type phonograph, 12 is the turntable, 13 is the stem driven by the mechanism of the phonograph (not shown) which rotates 75 the turntable and 14 is a wax record rotating with the turntable.

The mechanism 21 has a base plate 22 and a cover casting 23 which house and protect certain moving parts of the mechanism. A 80 hollow shoe 24 engages the record and rotates therewith by means more fully described hereafter. The stem of this shoe is pivoted vertically between the base plate 22 and the cover 23 and carries the worm 25 85 engaging the worm wheel 26 mounted on horizontal shaft 27. This shaft is pivoted in the cover 23 and carries the worm 28 which engages worm wheel 29. This construction provides for the rotation of wheel 29 from the rotation of the turntable at a 90 greatly reduced speed.

The worm wheel 29 is loosely mounted on vertical shaft 30; to this shaft the clutch member 31 is secured by pin 32. This member 95 engages a concave recess in wheel 29 forming a friction clutch. A coil spring 33 holds the clutch in engagement and it is de-clutched by the movement of the slide 37 which is provided with the incline 38; a 100 movement to the right by pressure on lug 36 moves the incline under the loose collar 40 forcing it upward to engage the screw 39 thereby elevating the shaft 30 and releasing the clutch member 31 from the wheel 105 29, the latter being prevented from rising by the rim 34 cast integral with the cover 23. When this slide is moved back by pressure on lug 35 the incline is removed from under the collar 40 and spring 33 restores 110

the friction clutch in engagement with wheel 29. It will thus be observed that when the friction clutch is released shaft 30 is not driven by the stem of the turntable.

5 Fig. 3 shows a plan view of the releasing slide. This is guided to slide in a horizontal plane by a groove in the boss of the casting 23, the top of the slide 37 being flush with the projecting sides of the boss. A slotted 10 opening for shaft 30 permits the sliding motion and limits its extent.

The vibrations of the record are transmitted by a device known as a tone arm 44 supporting the diaphragm casing 46. This tone 15 arm is attached by a ball joint to the voice tube 43 and secured by the pivot screws 45 so as to have a free vertical motion. This voice tube is carried by the foot 42 of the shaft 30 and is subject to the movements of 20 this shaft; that is to say the motion of the stem of the turntable can be used to move the diaphragm and the stylus 47 slowly across the face of the record about the center 30 describing the arc indicated by the dotted line α . The simultaneous rotation of the turntable and the rotation of shaft 30 causes 25 stylus 47 to inscribe a finely divided spiral groove on the face of the record. The elevation of shaft 30 partially raises the stylus 30 from the record. This effect, however, is increased by the lever effect secured by the bent piece 48 fixed to the tone arm 44. When the foot 42 is raised this piece engages the base plate 22 thus turning the tone arm on 35 pivots 45 and raising stylus 47 from the record with a comparatively large clearance.

It has been stated that raising the shaft 30 releases the friction clutch and thus leaves 30 the tone arm entirely free to be moved to any 40 position on the record. This is an important feature of my invention as it enables the stylus to be accurately positioned in any groove of the record without "back-lash" or "lost motion."

45 An index 82 is provided on the base plate 22 over which the pointer 81 carried by the tone arm moves to indicate the position of the latter on the record.

When the tone arm moves toward the center 50 of the record it is essential that its motion be stopped before engaging the center stem of the turntable. This is provided for by the releasing pin 83 in the foot 42 of shaft 30 engaging the incline 84 of the casting 51,

55 Fig. 5, also shown projected in detail A. As this pin rides up the incline the friction clutch is released by raising the foot 42, this action also raises the tone arm from the record as above described.

60 The casting 51 is screwed to the base plate 22 at 53 and is therefore a fixed part of the instrument, the speaking tube is connected to the stem 52 of this casting through which the opening 64 is provided connecting with 65 the circular chamber indicated by the broken

line 91, Fig. 5. Intersecting one side of this chamber is the foot 42 moving on and with the shaft 30. This foot is a cylindrical hollow member through which the voice tube 43 passes and the end opening indicated at 92 70 of this tube connects with the circular opening 91. It will thus be observed that while foot 42 may move through a considerable angle a clear and unobstructed passage is provided for the sound which, however, is 75 confined within the voice duct as defined by the circular opening 91. It is thus possible to attach the speaking tube to a fixture of the mechanism while the tone arm is free to move.

It has been stated that the mechanism is 80 driven from the stem of the turntable by means of a friction clutch. This is illustrated in Figs. 1 and 4. It is found in practice that the stem of these machines seldom runs true, usually there is a certain degree 85 of eccentricity which, if not provided for, would cause the mechanism to oscillate and produce a corresponding motion in the stylus of the tone arms. I provide for this by a special form of universal joint having a friction sleeve 71 with saw cuts 72 which grips the stem 13 by a spring action. A pin 73 passes through the head of this stem and through the slots 77 in the shoe 24, rounded fillers 74 are placed on the ends of pin 73 and 90 take up the space 78 between the sleeve 71 and the shoe 24. Pin 73 transmits the rotation of sleeve 71 to shoe 24 while the space 78 permits a certain amount of eccentricity of 95 sleeve 71 that is not imparted to shoe 24. 100 This shoe, therefore, rotates in a vertical and rigid position as maintained by the screw 59. The stem 13 is usually of a definite length but the height of the record 14 may vary, a centering washer 79 is provided in the record 105 of a universal thickness, the friction sleeve 71 is forced over the stem 13 by means of pin 73 until it engages this washer thus providing a substantial friction surface for driving the mechanism; the slot 77, however, 110 permits the elevation of shoe 24 to accommodate the various thickness of record. This arrangement also establishes a constant height from the surface of the record to the base of the instrument and thus automatically maintains the stylus of the tone arm in 115 fixed relation to the surface of the record as it may be worn down.

The mechanism is secured to the top of the phonograph by the flange 63, the end of 120 screw 59 fits a jawed opening in flange 63 and is secured in position by knurled nut 62. Arm 58 is threaded on screw 59 and can, therefore, be elevated or lowered by turning knurled nut 60 and releasing nut 62 to permit screw 59 to rotate. A lock nut 61 secures this arm in position and prevents any tendency of the arm to rotate on screw 59. The casting 51 has a flat extension 54 to which the hinge piece 55 is secured by screws 13

56 in slotted openings as shown, this hinge piece pivots to the arm 58 at 57, the arm 58 thus supports one end of the mechanism and its height may be adjusted so as to maintain the base of the mechanism horizontal for records of any thickness and thus maintain the proper angle on the stylus of the tone arm. This mechanism may be applied to phonographs having turntables varying from seven to twelve inches in diameter, the horizontal adjustment in the hinge piece 55 is provided to enable flange 63 to be moved out from the center to clear the longer turntables. When this attachment is applied to a phonograph it is a convenience to be able to fix the sleeve 71 in the center of shoe 75 so that the position of flange 63 may thereby be more accurately located, this is secured by moving the sleeve upward within the shoe so that the head engages the opening 76 and is thereby alined with the stem of the shoe. In this position it can be applied to a turntable before the record is used, to position the flange 63.

25 The whole mechanism, it will be noted turns on the pivot 57, it can therefore be easily pulled away from the stem 13 and turned over so as to clear the turntable for renewing records. It is replaced by simply bringing it back into position and forcing friction sleeve 71 onto stem 13. The tone arm may be used for recording or reproducing, or a combination tone arm may be used performing both of these functions. The present invention shows a tone arm in outline only it being understood that various types of tone arm may be used with this mechanism, the tone arm itself not being a part of the present invention.

40 By the use of this invention it is possible to enhance the value of present disk type phonographs by an attachment that converts them into a recording as well as reproducing machines, that is simple to use, easy to apply and may be quickly and entirely removed from the phonograph. Having thus described my invention I claim:—

1. In a mechanism of the class described, the combination with a phonograph having a turntable with a stem, of a device detachably secured to the top of said phonograph and including a friction clutch, a tone arm pivoted vertically in said device and arranged to move in an arc across the face of said turntable, a driving mechanism for said tone arm operating through said friction clutch, said driving mechanism connected with the end of said stem.

2. In a mechanism of the class described, the combination with a phonograph turntable of a vertical shaft and a friction clutch, said shaft driven from the stem of said turntable through said friction clutch, a tone arm carried by said vertical shaft across the face of said turntable and means for re-

leasing said friction clutch by the movement of said tone arm.

3. In a mechanism of the class described, the combination with a phonograph having a turntable with a stem, of a device detachably secured to the top of said phonograph and including a friction clutch, a tone arm pivoted vertically in said device and arranged to move in an arc across the face of said turntable, a driving mechanism for said tone arm connected with the end of said stem and operating through said friction clutch and means for releasing said friction clutch and raising said tone arm from the record.

4. In a mechanism of the class described, the combination with a phonograph having a turntable with a stem, of a device detachably secured to the top of said phonograph and including a friction clutch, a tone arm pivoted vertically in said device and arranged to move in an arc across the face of said turntable, a stylus carried by said tone arm and following a finely divided spiral on the face of said record and means including said friction clutch whereby said stylus may be positioned in any groove of said spiral.

5. In a mechanism of the class described, the combination with a phonograph turntable supporting a record, of a vertical shaft and a friction clutch, said shaft driven from the stem of said turntable, a tone arm carried by said vertical shaft across the face of said record, and means for automatically releasing said friction clutch when said tone arm has moved to a predetermined position on said record.

6. In a mechanism of the class described, the combination with a phonograph turntable supporting a record, of a spring clutch engaging the stem of said turntable, a shaft and a friction clutch, said shaft driven by reduction gearing from said spring clutch through said friction clutch, a tone arm carried by said shaft across the face of said record, means for applying said spring clutch and means for releasing said friction clutch.

7. In a mechanism of the class described, the combination with a phonograph turntable supporting a record, of a spring clutch engaging the stem of said turntable, a vertical shaft located near the edge of said turntable, a friction clutch, said shaft driven from said spring clutch through said friction clutch, and a tone arm carried by said shaft across the face of said record to follow a spiral groove thereon.

8. In a mechanism of the class described, the combination with a phonograph, of a turntable supporting records of various thickness, an attachment including a mechanism supported at one end from the center of said record and at the other end from a support secured to said phonograph, said mechanism supporting a tone arm pivoted vertically, a spring clutch engaging the stem of said

turntable and arranged to move said tone arm in the arc of a circle, means positioning said tone arm at a uniform height from the surface of said record and means for engaging said spring clutch uniformly with records of different thickness.

9. In a mechanism of the class described, the combination with a phonograph, of a turntable, an attachment including a mechanism supported at one end from the center of said turntable and at the other end from a support secured to said phonograph, a pivot connection between said mechanism and said last mentioned support, said mechanism having a vertical shaft and carrying a tone arm to move across said turntable in the arc of a circle, said mechanism being turnable on said pivot to clear said turntable.

10. In a mechanism of the class described, the combination with a phonograph, of turntables of various diameters, a mechanism having a vertical shaft carrying a tone arm pivoted to move across said turntable in the arc of a circle and supported at one end from the center of said turntable and at the other end from a support secured to said phonograph, means for changing the position of said last mentioned support with relation to the center support whereby said mechanism may be adapted to the diameter of said turntable.

11. In a mechanism of the class described, the combination with a phonograph turntable, of a device engaging the stem of said turntable, a mechanism detachably secured to the top of said phonograph having a vertical member carrying a tone arm across said turntable in the arc of a circle, a universal joint connecting said device with said mechanism whereby a steady motion is imparted to said tone arm.

12. In a mechanism of the class described, the combination with a phonograph, of a turntable, having a stem, a device detachably secured to a support on the top of said phonograph close to and extending above said turntable, a horizontal arm pivoted vertically to said device and arranged to move across the face of said turntable in the arc of a circle, means for moving said tone arm, a voice duct to said tone arm fixed to said device and means for maintaining said voice duct to said movable tone arm.

13. In a mechanism of the class described, the combination with a phonograph, of a turntable, having a stem, a device detachably secured to a support on the top of said phonograph, said device pivoted to turn back on said support to clear said turntable, a tone arm rotatably supported by said device, and driven from said stem, a horizon-

tal voice duct to said tone arm fixed to said device, an expanded chamber in said horizontal voice duct and the end of said tone arm moving within said chamber.

65

14. In a mechanism of the class described, the combination with a phonograph, of a turntable supporting a record, a mechanism supported at one end from the center of said record and at the other end from a support secured to said phonograph, said record having a centering washer on its lower surface to fit the stem of said turntable, a spring clutch engaging the stem of said turntable and operating said mechanism and a space in said record above said washer to permit said spring clutch to engage said stem.

70

15. In a mechanism of the class described, the combination with a phonograph, of a turntable supporting a record, a mechanism supported from the center of said record by a shoe, said hollow shoe having parallel slots, a spring clutch within said hollow shoe engaging the stem of said turntable and a pin connecting said spring clutch with said parallel slots.

85

16. In a mechanism of the class described, the combination with a phonograph turntable, a mechanism supported by a hollow shoe from the center of said turntable a spring clutch within said hollow shoe engaging the stem of said turntable, a universal joint connection between said shoe and said spring clutch and means whereby said spring clutch may be rigidly locked in said hollow shoe.

90

17. In a mechanism of the class described, the combination with a phonograph turntable of a mechanism including a vertical shaft and a friction clutch, said shaft driven through said clutch from the stem of said turntable, a tone arm carried by said vertical shaft, a sliding member having an inclined plane incorporated in said mechanism and means including said sliding member for releasing said friction clutch.

100

18. In a mechanism of the class described, the combination with a phonograph turntable of an attachment including, a mechanism with a spring clutch engaging the stem of said turntable, a universal joint, a worm gear, a horizontal shaft, a second worm gear, a friction clutch, a vertical shaft, said vertical shaft driven from the stem of said turntable through said universal joint, worm gears, horizontal shaft and friction clutch, and said vertical shaft arranged to move a tone arm across the face of said record.

110

Signed at New York in the county of New York and State of New York this 7th day of October A. D. 1919.

WILLARD H. GILMAN.
